GUN PERFORATOR

Robert R. Thompson and Whitman D. Mounce,
Houston, Tex., assignors to Standard Oil De-
velopment Company, a corporation of Dela-
ware

Application October 17, 1940, Serial No. 361,514

5 Claims. (Cl. 164—0.5)

The present invention is directed to a firing chamber for a bore hole gun and a method for loading same.

Bore hole guns are used for perforating casing in oil wells. As may well be recognized, very great pressures must be developed behind the bullets before they are projected in order that they may penetrate, in some cases, several thicknesses of casing as well as cement between the strings. Since the barrel from which the bullet must be projected is necessarily short, the time for developing the projecting pressure is also very short. Consequently, the development of a sufficiently high projecting pressure has been one of the major problems in the construction and use of bore hole guns.

The art has almost universally resorted to mechanical means for holding the bullet in place in the barrel until sufficient pressure is developed behind it. The mechanical means has assumed the form of a washer embedded in a recess in the gun barrel and having sufficiently small internal diameter to form a stop for a flange on the inner end of the bullet, whereby the bullet is not projected until sufficient pressure is built up behind it to either shear off the flange on the rear end of the bullet or shear off the washer. The provision of this washer, of course, necessitates the making of the barrel in parts so that, after a shot, the washer can be replaced. This has been found unsatisfactory for the reason that the strain exerted on the parts is such as to distort the threads connecting them and thereby limit the number of times the parts can be separated and reassembled.

The present invention is based on the discovery that the use of mechanical restraining means can be avoided by the simple expedient of using the bullet as a ram for compressing the powder into the powder chamber. That is to say, in the practice of the present invention the barrel is filled with powder and then the bullet is forced into the barrel by sufficient pressure to compress the powder into the firing chamber at the rear end of the barrel. It has been found that, as a result of this compression, that portion of the powder which is immediately behind the bullet is consolidated to a degree approaching that attainable by fusion and that this degree of consolidation decreases toward the rear end of the 50

It has been ascertained that it is not the degree of consolidation alone which accounts for the results flowing from the procedure of the present invention; that is to say, a charge of 55

powder can be compressed separately to the same degree to which it is compressed in the practice of the present invention and then placed in the firing chamber and the bullet arranged in front of it without making possible the development of a sufficient projecting pressure. As a matter of fact, when the gun is loaded in this manner, it is wholly inoperative, since the pressure developed is sufficient only to push the bullet out of the barrel without any penetrating force.

By the practice of the present invention, on the other hand, greatly increased efficiency of the powder can be realized. For example, the same penetration can be obtained by the practice of the present invention with one-third of the powder charge that is necessary when the previous practice of using mechanical restraining means on the bullet is resorted to. Thus, it appears that something occurs during the compression of the powder by the bullet, whether it be the establishment of an intimate adhesion between the powder and the walls of the firing chamber or the setting up of a cementing layer between the bullet and the interior of the barrel, which accounts for the unexpected results attained. No attempt is here made to explain why the improved efficiency is secured.

It may be noted here that, for the practice of the present invention, it is preferred to use a fine-grained powder, particularly one which is fast burning. The greater the size of the grains of the powder, the less is the advantage realized by the procedure constituting the present invention.

35 As will be understood from the above discussion, the present invention makes possible the use of a single integral element, which constitutes both the barrel and the firing chamber. As a feature of this invention there is provided a readily replaceable firing filament which is not mechanically connected to the firing chamber whereby the gun may be readily reloaded.

40 Further objects and advantages of the present invention will appear from the accompanying drawings in which

Fig. 1 is a vertical section of a portion of a bore hole gun with a gun barrel embodying the features of the present invention shown in place;

Fig. 2 is a front view of a similar section of a gun body showing the manner of holding the gun barrel in place;

Fig. 3 is a vertical section of the gun barrel showing the position of the powder at the beginning of the charging operation; and

Fig. 4 is a similar view showing the position of a bullet and the powder at an intermediate stage of the charging operation.

Referring to the drawings in detail, numeral 1 designates a gun body which, as is known, is ordinarily a long cylindrical bomb connected to the surface by a cable carrying electrical conductors and being provided with a plurality of wells 2 in which are arranged gun barrels. In this particular instance, the gun barrel 3 is a cylinder of suitable metal having a central recess 4 extending from its outer end nearly to its inner end, said central recess being connected to the other end of the barrel 3 by a passage 5 of smaller diameter which serves the purpose hereinafter specified.

Intermediate the ends of recess 4 is a shoulder 6 which separates the firing chamber from that portion of the recess which accommodates the bullet 7. This shoulder plays an important part in the practice of the present invention since, by its location, the degree of the compression of the powder charge can be regulated so that any desired firing pressure can be attained. It may be mentioned that this shoulder is not always absolutely necessary for the practice of the present invention, but it is distinctly advantageous in guns to be used in deep bore holes where high hydrostatic pressures are encountered. In such cases, in the absence of the stop, the hydrostatic pressure in the bore hole would serve to compress the powder charge to the point where it might not ignite and, if ignited, would not have its normal efficiency.

Arranged in the inner end of recess 4 is a metal stud 8 carried by a stem 9 which passes through the passage 5 and extends beyond the inner end of the barrel 3 where it makes contact with a flat conducting strip 10 which is insulated from the gun body 1 by insulating strips 11 and is connected to a conductor 12 which, in turn, is connected to a resistor 13 which is arranged in the firing circuit which is supplied by power arranged at the surface. The stem 9 has a smaller diameter than the passage 5 and is held in spaced relation thereto and insulated from the walls thereof by packing rings.

The stud 8 is insulated from the gun barrel 3 by insulating packing 14 and has its inner face exposed to make contact with the prongs of a cotter pin 15 which passes through a pair of insulating disks 16 between which is arranged a metal disk 17, the edges of which are preferably serrated and upturned to press resiliently against the wall of the firing chamber. The firing filament 18 is connected between the top of the cotter pin and the disk 17. It may be noted here that the center portion of the disk is cut away so as not to come into contact with the cotter pin. The outer end of the pin 9 is surrounded by packing material 19 which constitutes a seal to prevent fluid from entering the firing chamber from the rear and holds the stem in spaced relation to the wall of passage 5.

As is shown, the gun barrel 3 is for the greater part of its length of a diameter such as to fit snugly in the well 2, while at its outer end it is of somewhat reduced diameter. A pair of diametrically opposed set-screws 20 are arranged in the gun body 1 with their ends adapted to thrust against the outer surface of the gun barrel 3 at a point where it has a reduced diameter in order to hold it in place. It will be understood, of course, that the gun barrel can be made of uniform diameter throughout its length

and provided with recesses to receive the set-screws.

Referring to Fig. 3, it will be noted that the first step in loading the gun barrel is to insert in place the small unit of disks carrying the cotter pin and firing filament. The entire recess 4 is then filled with powder. The bullet which is selected to fit the recess snugly is then inserted into the top of recess 4 and is pressed into place by any suitable press capable of exerting the desired pressure. For most operations it has been found that a small hand press is sufficient for this purpose. As previously stated, the shoulder 6 in the recess 4 is so located that the desired amount of compression of the powder will be attained when the bullet sets on the shoulder. In practice, it has been found that when recess 4 has a diameter of $\frac{3}{8}$ of an inch at its larger end and $\frac{1}{8}$ of an inch at its smaller end and is $2\frac{1}{2}$ inches deep, suitable projecting compression can be obtained by arranging a shoulder about midway between the ends of the recess. The best location for the shoulder with different size guns can be ascertained by experiment. It is desirable to have a number of gun barrels of the same size, but with shoulders arranged at different points for use of different powders and for different degrees of penetration.

If desired, the open end of recess 4 can be plugged by a rubber stopper. This is not necessary, however, because another feature of the present invention is that by the practice thereof the powder immediately behind the bullet is so compacted as to form a fluid-tight seal for the remainder of the powder chamber. While reference has been made herein to a bullet it will be understood that a coring device is also contemplated within the general term "projectile."

The objects and advantages of the present invention having been thus described and illustrated, what is claimed as new and useful and is desired to be secured by Letters Patent is:

1. A well bore hole gun barrel comprising a metal body having an elongated recess therein having a sealed inner end, a projectile fitted into the open end of said recess, a powder charge compressed in situ in the inner end of said recess by said projectile said projectile being of a size to make a snug fit with said barrel and the compression pressure being of the order of that required to compress the powder in finely divided form to half its original volume, and a firing element in said powder charge.

2. A well bore hole gun barrel comprising a metal body having an elongated recess therein having a sealed inner end, a shoulder intermediate the ends of said recess, a projectile fitted into the open end of said recess and seated on said shoulder, a powder charge compressed in situ in the inner end of the recess by said projectile, said projectile being of a size to make a snug fit with said barrel and a firing filament in said powder charge.

3. A well bore hole gun barrel comprising a metal body having an elongated recess therein, a projectile fitted into the open end of said recess, an electrical contact arranged at the inner end of said recess, a removable element having a metal portion adapted to frictionally engage the wall of said recess and another metal portion insulated from the first adapted to engage said electrical contact and a filament connected to said metal portions arranged in said recess and a powder charge disposed around said filament

and compressed in the inner end of said recess by said projectile.

4. A method for loading a gun barrel of a well bore hole gun which comprises filling said barrel with loose fine grained powder to a point where it occupies a volume considerably in excess of its firing volume, inserting a projectile into the open end of said barrel, and applying pressure to said projectile to compress said powder

a predetermined amount said pressure being of the order of that sufficient to compress said powder to half the volume it originally occupied.

5. A method according to claim 4 in which a firing filament is first arranged in said barrel and is surrounded by said loose powder.
